5 Claims. (Cl. 29—177)

Various methods for producing clockwork dials provided with projecting symbols are already known, according to which the dial plate and the symbols are obtained through galvanoplastic means starting from a mold of insulating material, the surfaces of which are made conductive through metallization. The metallized layer may be removed at the end of the operation, or else, it may be retained for giving a color to the dial or to the symbols.

There are obtained thus dial plates of an electrolytic material, the grade of which is however lower than that of stamped plates. Furthermore, it is not possible to provide signs indicia or symbols made of solid gold without this leading to the production of dials also made of gold, or else, without resorting to an amount of gold which is much larger than that actually required for the formation of gold symbols alone.

My improved method allows executing clockwork dials which do not show such drawbacks.

According to my invention, a mold is produced inside which the impressions corresponding to the symbols or indicia are provided and through which a conductive member is inserted across the bottom surfaces of said impressions and, this being done, the surface of the impressions is rendered electrically conductive, the symbols are produced through an electrodeposition method, the mold is removed and the symbols are secured to the dial plate.

The accompanying drawing illustrates an embodiment of my invention, showing how this method may be executed.

FIGS. 1 to 9 of said drawing illustrate diagrammatically the main successive stages of said method.

According to said method, I begin by producing a mold 1 of plastic material (FIG. 1), for example of polyethylene, polystyrol, polyvinyl-chlorine or epoxydrosin, of which the upper section is provided with impressions for the formation of the symbols which it is desired to lay on a dial.

Mold 1 carries a conductive member 2 embedded inside it and forming the bottom of impressions, said conductive member being constituted, for instance, by an old dial. The impressions are obtained by means of a member 3 inserted, for instance, inside the mold of an injection molding apparatus, not shown, into which the plastic material forming the mold is to be injected. It being understood the mold is made with the member 2 in position in the die of the injection molding apparatus.

The surface of the mold (FIG. 2) is first coated with a thin layer of conductive material 4, say a copper layer, obtained through vacuum deposition and which has for its result an electric interconnection between the impressions and the conductive member 2. Of course, metals such as gold or silver can be used.

By means of a slight operation on a milling machine, for instance, this layer is removed from the upper surface of the mold so as to allow only that section of the layer which lines the impressions to remain in position. The mold is then dipped into an electrolytic bath, so as to form the symbols 5 by a filling, by electro-deposition, of the impressions, for instance by means of gold (FIG. 3). The latter is deposited only inside the recesses, since only these are then conductive.

This being done, the upper surface of the symbols is finished off by a surfacing by means of a diamond or by polishing (FIG. 4), after which the finished symbols are protected by means of a copper layer 6, for instance, 5 which is obtained electrolytically (FIG. 5).

Said protecting layer has a thickness such, say $\frac{1}{10}$ of a mm., which ensures a proper protection of said symbols.

Known means, for instance a welding through a resistance, or a welding by means of supersonic waves, 10 soldering, gluing or the like, are then resorted to for securing over the protecting layer 6 a support 7 which may be constituted, for instance, by a metal ring or plate.

The mold 1 is finally removed by melting or by chemical reagents which dissolve it, for instance and then 15 after, the conductive member 2 is removed by dissolving, for instance, the metallized layer connecting it with the gold or the like symbols; I obtain thus the complete hour scale secured to the support 7, as illustrated in FIG. 7.

20 The mold materials are dissolved as follows:

(a) *Polyvinylchlorine*—by way of example, is soluble in esters, and ketones, in cyclohexanon, in acetone, in ethyleneacetate, in methylenechlorine (and other solvents). Moreover, it softens and melts at temperatures 25 above 50° to 70° C.

(b) *Polystyrol*—is soluble in the above-mentioned solvents, and is also soluble in benzene. Moreover, it melts at temperatures above 80° to 100° C.

(c) *Polyethylene*—is, for example, soluble in hydrocarbons at temperatures above 65° C. It melts at temperatures above 90° to 150° C.

Further means also known per se and preferably a resistance welding or a supersonic welding, allow securing finally the symbols 5 onto a dial plate 8. The support 35 or carrier 7 is then removed together with the projecting layer carried by it, so as to provide for the appearance to view of the finished symbols which the different securing operations cannot damage by reason of the protecting layer 6 coating their parts subjected to such operations.

40 The removal of the support 7 may be obtained through a series of well-known means, say through electrolysis or through dissolution by an acid.

The upper surface of the dial plate, may, of course, be entirely finished, that is, it may have been previously 45 subjected to the usual finishing operations and, in particular, to the conventional electrolytic treatment.

My improved method is particularly economical since it allows obtaining dials carrying projecting symbols which are made, for instance, of gold, while resorting only 50 to the amount of gold which is strictly required for their execution. This is ascribable chiefly to the presence of the lead 2 embedded in the mold and subsequently removed. The dial plate may be obtained through any conventional means, for instance, through stamping. Lastly, 55 the symbols, as also the dial plate, can be finished independently of one another and the operations on the dial plate cannot damage the symbols and vice versa.

Of course, my invention is by no means limited to the method described hereinabove which may be subjected to 60 many modifications within the scope of the accompanying claims.

Similarly, the symbols may also be obtained separately for instance, through an electrolytic deposit of metal in a mold as before described where the dial to be used for fixing indicia thereon functions as the conductive member 2.

What I claim is:

1. A method for manufacturing a clockwork dial having indicia thereon in relief comprising, providing a dial having a major face to which indicia are to be secured and a form, forming the indicia simultaneously in spaced relative positions in said form corresponding to spaced

relative positions in which said indicia are to be fixed relative to each other on said major face of said dial with an area of each such indicia exposed, attaching a rigid carrier to said area of each such indicia to maintain said indicia in said relative positions upon removal of said form, removing said form from said indicia, positioning said carrier and indicia attached thereto in position with said indicia between the dial and carrier with said indicia in contact with said major face of said dial to which said indicia are to be secured, permanently securing the indicia on said dial in said relative positions, and removing said carrier.

2. A method for manufacturing a clockwork dial having indicia thereon in relief comprising, providing a dial having a major face to which indicia are to be secured and a form having spaced form cavities thereon, coating only the inner surface of said cavities with a conductive coating and providing an internal current flow path to said inner surfaces, depositing metal only in said cavities by electrodeposition for forming the indicia in spaced relative positions in which said indicia are to be fixed relative to each other on said major face of said dial with an area of each such indicia exposed, attaching a rigid carrier to said area of each such indicia to maintain said indicia in said relative positions upon removal of said form, removing said form from said indicia, positioning said carrier and indicia attached thereto in position with said indicia between the dial and carrier with said indicia in contact with said major face of said dial to which said indicia are to be secured, permanently securing the indicia on said dial in said relative positions, and removing said carrier.

3. A method for manufacturing a clockwork dial having indicia thereon in relief comprising, providing a dial having a major face to which indicia are to be permanently secured, providing a dissolvable form having cavities therein for forming the indicia, the cavities being electrically connected internally of the mold rendering the inner surfaces of said cavities electrically conductive, depositing material in said cavities only during application of electrical current to said cavity inner surfaces to form said indicia, said cavities being disposed spaced relative to each other in position corresponding to the spaced relative positions said indicia are to occupy relative to each other when secured to said dial, attaching a rigid carrier to all of said indicia subsequent to the deposition thereof to hold said indicia in fixed relative positions upon removal of said form, dissolving the form to free the indicia therefrom, positioning the carrier for securing the indicia on said dial, permanently securing said indicia on said dial, and removing the carrier from said indicia so that the indicia remain fixed in position on said dial free of said carrier.

4. A method for manufacturing a clockwork dial having indicia thereon in relief comprising, providing a dial having a major face to which indicia are to be permanently secured, providing a dissolvable form having cavities therein for forming the indicia, the cavities being electrically connected internally of the mold rendering the

inner surfaces of said cavities electrically conductive, depositing material in said cavities only during application of electrical current to said cavity inner surfaces to form said indicia, said cavities being disposed spaced relative to each other in position corresponding to the spaced relative positions said indicia are to occupy relative to each other when secured to said dial, attaching a rigid conductive carrier to all of said indicia subsequent to the deposition thereof to hold said indicia in fixed relative positions upon removal of said form, dissolving the form to free the indicia therefrom, positioning the carrier with indicia thereon in position relative to said major face of the dial for securing the indicia on said dial, applying welding current to said dial and carrier for permanently securing said indicia on said dial, and removing the carrier from said indicia so that the indicia remain fixed in position on said dial free of said carrier.

5. A method for manufacturing a clockwork dial having indicia thereon in relief comprising, providing a dial having a major face to which indicia are to be permanently secured, providing a dissolvable form having cavities therein for forming the indicia, the cavities being electrically connected internally of the form rendering the inner surfaces of said cavities electrically conductive, depositing material in said cavities only during application of electrical current to said cavity inner surfaces to form said indicia, said cavities being disposed spaced relative to each other in position corresponding to the spaced relative positions said indicia are to occupy relative to each other when secured to said dial, applying a protective coating to an exposed end of said indicia in said cavities, prior to applying said coating finishing surfaces on said indicia on which said coating is applied, attaching a rigid carrier to all of said indicia over said coating subsequent to the deposition thereof to hold said indicia in fixed relative positions upon removal of said form, dissolving the form to free the indicia therefrom, positioning the carrier with indicia thereon in position relative to said major face of the dial for securing the indicia on said dial, permanently securing said indicia on said dial, and removing the carrier from said indicia so that the indicia remain fixed in position on said dial free of said carrier.
